[57] CLAIM

The ornamental design for a food serving bowl, as
shown and described.

DESCRIPTION

FIG. 1 is a top plan view of a food serving bowl showing
our new design;

FIG. 2 is a side elevational view;

FIG. 3 is an end elevational view;

FIG. 4 is a bottom plan view;

FIG. 5 is an elevational view of the side opposite that
shown in FIG. 2; and

FIG. 6 is an elevational view thereof of the end opposite
that shown in FIG. 3.
